UNITED STATES PATENT OFFICE.

WILLIAM E. YOUNG, OF BALTIMORE, MARYLAND, ASSIGNOR TO WILLIAM A. TOTTLE & CO., INC., A CORPORATION OF MARYLAND.

FERRULE-SHAPING MACHINE.

Application filed November 3, 1920. Serial No. 421,479.

To all whom it may concern:

Be it known that I, WILLIAM E. YOUNG, a citizen of the United States, residing at Baltimore, in the State of Maryland, have 5 invented a certain new and useful Improvement in Ferrule-Shaping Machines, of which the following is a specification.

My present invention relates particularly to a ferrule-shaping machine, adapted to be 10 operated by power.

An object of my invention is the application of mechanical power in the giving of a desired configuration to closed metallic bands, or the like, and especially the shaping 15 of bands or ferrules such as are commonly comprised in the heads of paint brushes used by house painters.

Brushes of the type referred to are usually provided with a handle of wood or 20 the like, at one end of which is secured a body of bristles, or their equivalent, and the band or ferrule referred to, may be comprised of a section of drawn metal, or may be formed by cutting transversely a hollow 25 cylindrical body or by uniting the ends of a suitable piece of sheet metal.

The ferrule referred to, when used on a paint brush, is typically so employed as to secure, hide, and protect the joint between 30 the handle and the fibres, or the like, that constitute the head of the brush.

Before being put in place on the head of the brush, such a band is ordinarily in need 35 of a final shaping, which shaping must of course secure a fairly accurate correspondence with the transverse sectional configuration of the brush upon which the band is to be used. As brush holders are manufactured not only in large quantities but in a 40 great variety of sizes and styles, the foregoing implies the need of a capacity for alterations, by adjustment or substitution, in those elements of the band-shaping machine which determine the final size and 45 configuration of the band; and the objects of my invention include a facilitating of such adjustments or substitutions; and the objects thereof also include the providing of a machine, capable of a wide variety of 50 uses in addition to those mentioned, which shall be compact, rugged, rapid, safe, attractive in appearance, and provided with a means for the application of power and the immediate and easy control of an operator 55 who, the desired adjustments or sub-

stitutions having been made, need only place the band to be shaped upon the work-engaging elements hereinafter described, and then move a lever to secure application of power from an outside source thereto.

60

Further objects of my invention will appear from the detailed description set forth hereinafter, and, while my invention is capable of embodiment in many different forms, for the purpose of illustration I have 65 shown only certain forms of my invention in the accompanying drawings, in which:

Fig. 1 is a front elevation of a preferred embodiment of my invention.

Fig. 2 is an end elevation as viewed from 70 the left of Fig. 1, but not including the casing 30, nor the drive pulleys 31, 31', shown at the right of Fig. 1.

Fig. 3 is a vertical longitudinal section corresponding to Fig. 1, and, for the most 75 part, in the plane of the main drive shaft, that is to say, on line 3—3 of Fig. 2.

Figs. 4 and 5 are vertical transverse sections, on lines 4—4, and 5—5 respectively of Fig. 1, looking in the direction of the 80 arrows.

Fig. 6 is a plan view.

In the form of my invention herein shown, there is a hollow main casting, frame, or housing 24, which may rest upon 85 any suitable foundation, and which in turn preferably supports both the work-engaging parts 14, 14' and the actuating mechanism therefor.

Although any suitable source of power 90 may be used, I have herein shown a speed-reducing drive mechanism comprising tight-and-loose pulleys 31 and 31', the outermost pulley being preferably secured, by means such as collar 33, against lateral movement 95 on the shaft 18. The shaft 18, shown as carrying only a gear 19, preferably keyed thereto, may be supported in any suitable way, as by (1) the double bracket 29 (carrying also the main shaft 32), and (2) a 100 suitable ring or rings for securing one or both ends in casing 24.

The work-engaging parts or posts 14, 14' may be of any desired external or transverse configuration, and one or both of them 105 may be removably and adjustably secured, to facilitate either a change in the form and curvature given to the ends of bands worked upon, or a change in the distance therebetween—the latter change being made when-

110

ever, the requirements as to thickness and type of brush remaining unaltered, there are to be handled successive batches of bands or ferrules differing only as to the 5 width or longer transverse diameter of the brush heads in which or upon which they are to be used.

While it will be obvious that the desired shaping action might be attained by a suitable movement on the part of either or both of the work-engaging posts referred to, I have shown in the drawings a fixed post 14 as secured by machine screws to the main frame 24, appropriate means being, 10 however, provided for guidance and adjustment as well as reciprocation of the corresponding post 14'.

It being desirable that the work-engaging posts 14, 14' shall be conveniently positioned 20 for the placing and removal of successive bands or ferrules to be shaped or stretched thereby, I have preferred to make provision such as an undercut channel in the top of the main casting 24. In this channel I 25 have shown a reciprocating element which, for convenience, I hereinafter designate as carriage 21, and which is shorter than the mentioned channel in which it moves. It may conveniently be given the desired alignment and security in said channel by means 30 such as the adjustable and removable spacing plate or gib 12. Said gib in turn may be secured in any suitable manner, as by pins 26, each preferably provided with a 35 lock nut or nuts 39, the reciprocating carriage 21 being free to slide relatively to the said plate or gib 12.

To the rearward end of the carriage 21 I prefer to secure, by any convenient means, 40 such as bolts or screws 40, a threaded bearing element 13, to receive a corresponding long adjusting screw 8, to one end of which screw I may secure suitable actuating means such as the crank 28, shown as provided 45 with handle 15, the other end of the shaft of screw 8 being preferably provided with a circumferential groove to secure thereto, by means such as pins 41, a slideable element 11 carrying the work-engaging post 14',— 50 which may be removably secured thereto for convenient substitution, by means such as screws 42.

If desired, a set screw 43 may be provided in the threaded bearing block 13, to secure 55 in any adjusted position the mentioned screw 8, the preferred construction being such that whenever, to effect the expanding or shaping of a band placed over the posts 14, 14', the carriage 21 shall be reciprocated, 60 the crank 28 and all associated parts must reciprocate therewith.

To effect the desired reciprocation of the carriage 21, any convenient means may be employed, and in the present embodiment 65 of the invention I have imparted the desired

reciprocating motion by means of an arm 25, shown as depending from the plate 43, which plate may be secured, by means such as screws 44, to the bottom of the carriage 21. The arm 25 preferably carries means 70 such as pin 17, which may be provided with rollers 22, and may be secured by a set screw 45, for effecting contact with cam grooves in discs 1, shown as rigidly mounted on the main shaft 32, which is adapted for occasional or intermittent rotation.

As shown, shaft 32 may have one of its bearings in the bracket 29, screwed to the main frame or housing 24, and its other end may advantageously be provided with a friction collar 10, preferably keyed thereto and shown as capable of rotation in a split bearing provided with adjustable means for a braking effect, such a bearing being shown at 3, secured at 38, the lubrication of the 80 shaft being, however, provided by means such as Winkley oiler 35, with lubricating sleeve 5, the function of the described brake organization being a prompt retardation in the main shaft 32, and of the described reciprocating means driven therefrom, whenever the power shall be thrown off from the said shaft, as may be done by means hereinafter described.

On the main shaft 32 there are mounted 95 any suitable means for transmission of power thereto from the gear 19, heretofore mentioned. It would obviously be possible to transmit suitable motion to the shaft 32 in a continuous manner, thereby occasioning a rythmical reciprocation of the post 14' relative as to the post 14, the operative being then expected to utilize, for the placing and removal of the bands to be stretched, those intervals when the posts are relatively close 100 together. I, however, prefer to provide means such as a clutch and stop mechanism for transmitting motion to the main shaft 32, and thereby to the post 14', the said clutch being preferably under manual control through means such as lever 2, herein shown as pivoted to the main frame 24, and normally held in its rearward or rest position by means such as the spring 16.

In the construction shown, the forward movement of the lever 2, elevating the hook 46, and causing the engagement thereof with a pin or stud 47 on the cam-faced lever 48, pivoted at 49, and depressed by the spring 18, permits the curved or practically circular leaf spring 50 to force the pin 51 into the path of the heads of the bolts 20, which heads project from the face of idly revolving effect clutch gear 27, constantly driven by the gear 19 (and preferably protected by a casing 30) to thereby cause the clutch element 52 (carrying the tripper 53) to revolve therewith and to rotate the main shaft upon which it is mounted—all for the purpose and with the effect above described.

It is in order to limit the effect of the movement of the lever 2 to a single reciprocation of the post 14' that means such as the mentioned tripper 53 are provided, and this tripper is so placed on the clutch element 52 that, even if the operative happened to fail promptly to release or return the lever 2, the first revolution of the clutch element 52 will automatically, by contact with the said tripper with a face 54 of the hook 46, cause a disengagement of the lever from the stud on the cam-faced lever 48,—the depression of which, under the action of the spring 18, will, by the engagement of the cam face with the notch in the pin 51, cause a retraction of said pin and thereby a disengagement of the clutch, all parts being incidentally returned to their original position.

From the foregoing it will be apparent that, upon the placing of a band over the posts 14 and 14', and the pulling of the lever 2, there is caused a single reciprocation of one of the posts, and the parts are thereafter brought promptly to rest in a position suitable to a repetition of the described operation.

What I claim is:

1. In a band shaping machine, a fixed post and a movable post mounted on a carriage, a power shaft and a second shaft, means connected to the latter and the carriage for reciprocating it, a clutch for connecting the shafts, and automatic means for disengaging the clutch comprising a tripper 35 rotating with the clutch.

2. In a band shaping machine, a fixed post and a movable post mounted on a carriage, a power shaft and a second shaft, means connected to the latter and to the carriage for reciprocating it, a clutch for connecting the shafts, and automatic means for disengaging the clutch comprising a spring and a pin advanced thereby for causing the second shaft to be rotated, said pin being 45 provided with means for engagement in rotation by a cam faced lever which may be withdrawn by a hook engaging a stud thereon, said hook being arranged for automatic disengagement by a tripper.

3. In a band shaping machine, a fixed post and a movable post mounted on a carriage, said posts being adjustable in their positions, a power shaft and a second shaft, means connected to the latter and the carriage for reciprocating it, a clutch for connecting the shafts, and automatic means for disengaging the clutch comprising a tripper 55 rotating with the clutch.

4. In a ferrule shaping machine, a main casting carrying a post secured thereto, a carriage capable of reciprocation relative to said casting and carrying a second post, means on said carriage and reciprocating therewith for adjustably positioning said last mentioned post, a main shaft extend-

ing through said casting and adapted for occasional rotation, means for driving said shaft, and adjustable means for applying a braking pressure to said shaft.

5. In a ferrule-shaping machine, a main 70 casting carrying a removable post rigidly secured thereto, a carriage capable of reciprocation relatively to said casting and carrying a second post removably secured thereto, means on said carriage and reciprocating therewith for adjustably positioning said last-mentioned post, a main shaft extending through said casting and adapted for occasional rotation, means for driving said shaft, and adjustable means for applying a 75 braking pressure to said shaft.

6. In a ferrule-shaping machine, a main casting carrying a post rigidly secured thereto, a carriage capable of reciprocation relatively to said casting and carrying a 85 second post, means on said carriage and reciprocating therewith for adjustably positioning said last mentioned post, a main shaft extending through said casting and adapted for occasional rotation, means for 90 driving said shaft, a gear on said shaft, clutch means for causing said gear to rotate said shaft, and means for automatically disconnecting said clutch means.

7. In a ferrule-shaping machine, a main 95 casting carrying a post rigidly secured thereto, a carriage capable of reciprocation relatively to said casting and carrying a second post, means on said carriage and reciprocating therewith for adjustably positioning said last-mentioned post, a main shaft extending through said casting and adapted for occasional rotation, means for driving said shaft, a gear on said shaft, and clutch means under manual control and comprising 100 a spring and a pin advanced thereby for causing said gear to rotate said shaft, said pin being provided with means for engagement in rotation by a cam-faced lever.

8. In a ferrule-shaping machine, a main 110 casting carrying a post rigidly secured thereto, a carriage capable of reciprocating relatively to said casting and carrying a second post, means on said carriage and reciprocating therewith for adjustably positioning 115 said last-mentioned post, a main shaft extending through said casting and adapted for occasional rotation, means for driving said shaft, and clutch means under manual control and comprising a spring and a 120 pin advanced thereby for causing said gear to rotate said shaft, said pin being provided with means for engagement in rotation by a cam-faced lever, which lever may be withdrawn by a hook engaging a stud thereon.

9. In a ferrule-shaping machine, a main casting carrying a removable post rigidly secured thereto, a carriage capable of reciprocating relatively to said casting and carrying a second post removably secured 125 130

thereto, means on said carriage and reciprocating therewith for adjustably positioning said last-mentioned post, a main shaft extending through said casting and adapted 5 for occasional rotation, means for driving said shaft, and clutch means under manual control and comprising a spring and a pin advanced thereby for causing said gear to rotate said shaft, said pin being provided

with means for engagement in rotation by 10 a cam-faced lever, which lever may be withdrawn by a hook engaging a stud thereon, said hook being arranged for automatic disengagement by a tripper.

In testimony that I claim the foregoing, 15 I have hereunto set my hand this 29th day of October, 1920.

WILLIAM E. YOUNG.
